UNITED STATES PATENT OFFICE.

GEORGE LOCKHART, OF NEW YORK, N. Y.

LOCK.

1,184,189.

Specification of Letters Patent. Patented May 23, 1916.

Application filed August 5, 1912. Serial No. 713,215.

To all whom it may concern:

Be it known that I, GEORGE LOCKHART, a citizen of the United States, and resident of the city, county and State of New York, have invented certain new and useful Improvements in Locks, of which the following is a specification.

This device is intended as a lock such as is sometimes termed a safety brace or bar lock, wherein a bar is hingedly secured to a permanent fixture and is slidably engaged with a door or gate.

In the development of my invention I have devised numerous ways for accomplishing the desirable result, as I have found that different styles of doors require a different arrangement of the locking bar. The bar as arranged to operate on a sliding door being found impractical on a swinging door, and I have found that the lock necessary to secure a simple sliding door need not be so complicated as one required by a duplex door or gate. All of these arrangements, their construction and method of operation will be fully set forth as the specification progresses and it will be observed that the lock herein set forth may be used not only upon sliding elevator doors but also upon swinging doors or hinged covers or in any place where a strong lock is desired.

The following is what I consider the best means of carrying out this invention.

The accompanying drawings form a part of this specification, in which: Figure 1 shows in elevation the lock used on a double slide or elevator door. Fig. 2 shows in plan the device used on a swinging door. Fig. 3 shows in elevation a part removed. Fig. 4 shows in end elevation the part shown in Fig. 3. Fig. 5 shows a modification of the structure set forth in Fig. 2. In this modification two sliding bars are used. Fig. 6 shows the door in an open position.

Similar reference numerals indicate like parts in all the figures where they appear.

As the devices shown in the separate figures are alternate constructions differing from each other in many essential details, I will describe each separately.

Referring to Fig. 1, at 1, I have shown the locking bar, a straight flat bar of steel perforated at each end. A bracket 2 adapted to be screwed securely to a wall or other permanent support is provided with a ring 3, which passes through the perforations in one end of the rod 1 and produces therewith

a flexible joint adapted to be hinged vertically or slid horizontally. Arranged adjacent to the other end of the bar 1, I provide a rod 4 of any desirable length and which I have secured by means of sockets 5 and 6 and brackets 5^a and 6^a at a point quite close to the inner edge of a sliding door A. Slidable upon the rod 4 is a member provided with a grip 8, which is a cylinder through which the rod 4 is free to pass and formed integral with this cylinder are the outwardly extending lugs 9 and 10 each provided with a screw as shown at 11 and 12. These lugs 9 and 10 are formed of two parts of equal shape and size separated from each other a sufficient distance to allow the bar 1 to be inserted and there to be loosely held by means of either of the screws 11 or 12. I provide two of the lugs as shown at 9 and 10, but in operation I use but one, the other lug serving only if it is desirable to extend the bar 1 in the opposite direction, for operating a door having two or more sliding members. In operating this locking bar the hand is placed about the grip 8 and the grip is lifted or slid longitudinally upon the rod 4. The door may then be opened by causing it to slide toward the bracket 2. This will cause the end of the rod 1 and the grip 8 and parts secured thereto to travel upward on the rod 4 until the door is fully opened, and it is my intention that the parts shall be so arranged and conditioned that the rod 1, and grip 8 will only obtain such a position as will cause them to constantly tend to close the door.

If it is found desirable to secure the door open or closed a pin may be placed in one of the perforations 13, a series of which are shown in the rod 4.

If the door be of the construction as shown in Fig. 1 wherein the parts A and B slide back over the part C it becomes necessary to place an operating bar to move the part B. I do this by connecting to the lug 10 a rod 1^a pivotally connected to the part B at 3^b. Now lifting the grip 8 will cause the rod 1 and 1^a to be drawn inward and as the parts A and B are movable they will both slide back over the part C, the inner edge of the part B passing under the angle members 5^a and 6^a. And now referring to Fig. 2, a modified form, I have shown the rod placed in a horizontal position. This rod 20 is secured by means of the brackets 21 and 22 and slidable thereon I have arranged a

grip 23 though in this instance having the lug 24 arranged upon its front face. A locking bar 25 operable in this lug 24 and hingedly secured therein by means of a screw may also be a flat steel rod, but considerably shorter than the rod 1 shown in Fig. 1. A bracket 27 firmly secured to the wall or other permanent support receives the inner end of the bar 25, and hingedly retains it by means of the screw 28. A pin 29, which may be inserted into any one of a series of holes in the bar 20 locks the sliding member 23 in a predetermined position. The door to which the bar 20 is secured hinges at 30, and when this door is opening the member 23 slides upon the rod 20.

At Fig. 5, I have shown a modification of the structure shown in Fig. 2. I have found that some swinging doors are too narrow to accommodate a horizontal rod sufficiently long to allow the door to open fully. I have therefore placed a second slider rod 45, upon the permanent abutment, in lieu of the bracket 27. In this construction the members 46 and 47 will both slide allowing the door to open to its full extent, and as both the slider rods may be perforated it will require two pins 29 to secure the slides 46 and 47 in position.

It is obvious that these devices may be operated in conjunction with a key by merely placing a key operated abutment adjacent to the sliding members in Figs. 1 and 2, and by arranging a key to lift the inner projecting end of the bar 33 in Figs. 3 and 4.

Other modifications may be made within the scope of the appended claims without departing from the principle or sacrificing the advantages of this invention.

Having carefully and fully described my invention what I claim and desire to secure by Letters Patent is:—

1. The combination with a door having a

series of slidable sections, of a lock having a vertically disposed bar secured to one said slidable section, a handle member slideable upon said bar, a lever pivoted to said slideable member and pivotally engaged with another movable section, and a second lever pivoted to said slideable member and to a stationary abutment, the said handle member being adapted to return said levers to horizontal alinement and thereby close and lock the doors.

2. A door lock comprising a perforated rod arranged upon said door, a member slideable upon said rod, a lever pivoted to said slideable member and to a stationary abutment and adapted to be retained in a substantially horizontal position when the door is secured.

3. A device of the character described comprising a vertically disposed and perforated member, and means for supporting it upon a door, a member slideable longitudinally upon said perforated member and adapted to be secured thereon, a rod pivotally engaged with said slideable member and extending at an angle to said perforated member, said rod having one of its ends hingedly supported in a fixed and predetermined position as herein specified.

4. Controlling means for a plurality of complemental sliding door sections including pivots, arms extending from said pivots and adapted to swing thereon and sliding connections between said arms and said door section as and for the purpose set forth.

Signed at New York city, in the county of New York and State of New York, this 5th day of July, 1912.

GEO. LOCKHART.
